UNITED STATES PATENT OFFICE

2,469,485

BILL COMPARTMENT

Galen K. Weaver, Alliance, Ohio, assignor to The
McCaskey Register Company, Alliance, Ohio,
a corporation of Ohio

Application November 9, 1945, Serial No. 627,626

6 Claims. (Cl. 206—73)

1

The invention relates to bill compartments such as are provided in cash drawers for cash registers and the like, and more particularly to a bill compartment which eliminates the necessity of using the customary bill weight such as is commonly used in present practice.

Cash drawers as now in general use are provided with bill compartments of suitable dimensions to accommodate paper money in flat condition and are equipped with hingedly mounted bill weights which must be manually operated to place bills in or remove them from a compartment.

This not only necessitates continual manipulation by the operator whenever a transaction is made involving paper money, but since these compartments are of a size to accommodate the bills in flat condition, and several such bill compartments are provided in a cash drawer to accommodate bills of different denominations, they require a cash drawer of considerable size.

The object of the present invention is to provide a bill compartment which is so constructed that no bill weight is required to retain paper money therein.

Another object is to provide a bill compartment having bill engaging projections on its side walls.

A further object is to provide such a bill compartment with detachably mounted posts having bill engaging projections thereon.

A still further object is to provide a bill compartment of the character referred to so constructed that paper money is folded into U-shape when placed therein.

It is another object of the invention to provide a bill compartment so shaped and constructed that no manipulation is required other than the placing of the bills in the compartment or removing them therefrom.

The above objects, together with others which will be apparent from the drawing and following description, or which may be later referred to, may be attained by constructing the improved bill compartment in the manner hereinafter described in detail, and illustrated in the accompanying drawing, in which:

Figure 1 is a top plan view of a portion of a cash drawer showing two bill compartments constructed in accordance with the invention;

Fig. 2 a vertical, sectional view through the two bill compartments, taken as one the line 2—2, Fig. 1;

Fig. 3 a vertical, sectional view through one bill compartment, taken as on the line 3—3, Fig. 2;

Fig. 4 a detached, perspective view of one of the detachable posts, with bill retaining projections

2

thereon, such as used in a partition wall between two bill compartments; and

Fig. 5 a similar view of one of the posts such as used in the outer walls of the bill compartments.

The cash drawer, a portion of which is shown in the drawing and indicated generally at 10, may be formed of any suitable material, preferably molded in one piece as indicated in the drawing, and the bill compartments, indicated generally at 11, are formed in the drawer and preferably of the shape shown so that a bill is bent or folded into substantially U-shape as indicated in broken lines at B in Fig. 3.

If desired, the bill compartments may be of suitable dimensions to accommodate bills in flat condition but the shape of compartment illustrated is preferable as it requires so much less room in the drawer, and since several bill compartments are ordinarily provided in each cash drawer to accommodate bills of various denominations, a considerable saving in space is possible with the type of bill compartment illustrated.

As illustrated, two opposed walls 12 and 13 of each compartment may be straight sided and parallel while the other two walls, indicated at 14, are curved toward each other at their lower ends as at 15 merging into the bottom wall 16 of the compartment.

For the purpose of retaining the bills in each compartment, a plurality of projections such as the rounded knobs 17 may be provided upon the lower portion of each straight side wall 12 and 13, these projections on opposed walls being so spaced from each other that they will catch the edge portions of a bill when the same is inserted into the compartment, as indicated at B in Fig. 3.

Although the projections or knobs 17 may be formed integrally upon the side walls 12 and 13 of the bill compartment, they are preferably formed upon detachably connected members which may be removed and replaced in the event the projections become too badly worn by long use to properly retain the bills in the compartment.

For this purpose posts 18 and 19 may be provided, each provided with projections or knobs 17 and adapted to be detachably mounted so that the projections are in the proper position to retain the bills in the compartments.

The posts 18 may be located in suitable cut out portions 20 of partition walls and provided with projections or knobs 17 on opposite sides so as to accommodate two adjoining bill compartments, while the post 19 may be formed substantially

half round and adapted to be inserted into suitable cutout portions 21 in the end walls of the compartments and provided with projections 17 on only one side.

Each post 18 may be provided at its lower end with the annular shoulder 22 adapted to be received in the opening 23 in the bottom wall of the cash drawer and terminating in an enlarged annular flange 24 adapted to be received in the recess 25 in the bottom wall of the cash drawer, screws 26 or the like being provided to be received through the apertures 27 in the flange 24 and to be screwed into the bottom wall of the cash drawer to detachably mount the post 18 in position in a partition wall 13 between adjacent bill compartments.

Each post 19 may be provided at its lower end with the half-round shoulder 28 and half-round flange 29 adapted to be attached to the bottom wall of the cash register by screws 30 passing through apertures 31 in the flange 29.

The half-round shoulder 28 fits within a suitable opening 32 in the bottom wall of the cash drawer and the flange 29 is received within a recess 33 therein.

With this construction no bill weights are required and the only manipulation necessary is to place the bills down in the compartment in the manner shown in Fig. 3, the side edges of the bills engaging under the projections 17 and retaining the bills in the compartment, while no manipulation is necessary to remove a bill other than to grasp it in the fingers and pull it out of the compartment.

I claim:

1. A bill compartment for cash drawers and the like comprising two opposed straight sided walls and two opposed walls curved toward each other at their lower ends and merging into a bottom wall so as to define a compartment of substantially U-shape and of suitable dimensions to receive bills folded into substantially U-shape, and projections upon the vertical central portions of the two opposed straight sided walls located so as to engage over opposite edges of the central portions of the folded bills.

2. A bill compartment for cash drawers and the like comprising two opposed straight sided walls and two opposed walls curved toward each other at their lower ends and merging into a bottom wall so as to define a compartment of substantially U-shape and of suitable dimensions to receive bills folded into substantially U-shape, and vertically spaced, rounded projections upon the vertical central portions of the two opposed straight sided walls located so as to engage over opposite edges of the central portions of the folded bills.

3. A bill compartment for cash drawers and the like comprising two opposed straight sided walls and two opposed walls curved toward each

other at their lower ends and merging into a bottom wall so as to define a compartment of substantially U-shape and of suitable dimensions to receive bills folded into substantially U-shape, and detachable members located at the vertical central portions of the two opposed straight sided walls and having projections thereon located so as to engage over opposite edges of the central portions of the folded bills.

4. A bill compartment for cash drawers and the like comprising two opposed straight sided walls and two opposed walls curved toward each other at their lower ends and merging into a bottom wall so as to define a compartment of substantially U-shape and of suitable dimensions to receive bills folded into substantially U-shape, and detachable members located at the vertical central portions of the two opposed straight sided walls and having vertically spaced, rounded projections thereon located so as to engage over opposite edges of the central portions of the folded bills.

5. A bill compartment for cash drawers and the like comprising two opposed straight sided walls and two opposed walls curved toward each other at their lower ends and merging into a bottom wall so as to define a compartment of substantially U-shape and of suitable dimensions to receive bills folded into substantially U-shape, and detachable posts located at the vertical central portions of the two opposed straight sided walls and having projections thereon located so as to engage over opposite edges of the central portions of the folded bills.

6. A bill compartment for cash drawers and the like comprising two opposed straight sided walls and two opposed walls curved toward each other at their lower ends and merging into a bottom wall so as to define a compartment of substantially U-shape and of suitable dimensions to receive bills folded into substantially U-shape, and detachable posts located at the vertical central portions of the two opposed straight sided walls and having vertically spaced, rounded projections thereon located so as to engage over opposite edges of the central portions of the folded bills.
